The ornamental design for an electronics enclosure, as shown and described.

DESCRIPTION

FIG. 1 is a top, front, left perspective view of our design for an electronics enclosure;

FIG. 2 is a top plan view of our design in FIG. 1;

FIG. 3 is a bottom plan view of our design in FIG. 1;

FIG. 4 is a front elevation view of our design in FIG. 1;

FIG. 5 is a rear elevation view of our design in FIG. 1;

FIG. 6 is a left side elevation view of our design in FIG. 1; and,

FIG. 7 is a right side elevation view of our design in FIG. 1. In Figures 1-7, the broken lines are directed to environment, and are for illustrative purposes.

The broken lines in the drawings illustrate portions of an electronics enclosure which form no part of the claimed design.
